UNITED STATES PATENT OFFICE

154,433

DESIGN FOR A BEVERAGE BOTTLE CASE

Thur Schmidt, Chicago, Ill.

Application January 31, 1947, Serial No. 136,571

Term of patent 14 years

(Cl. D58—13)

To all whom it may concern:

Be it known that I, Thur Schmidt, a citizen of the United States, residing at Chicago, Illinois, have invented a new, original, and ornamental Design for a Beverage Bottle Case, of which the following is a specification, reference being had to the accompanying drawing, forming part thereof.

I claim:

The ornamental design for a beverage bottle case, as shown.

THUR SCHMIDT.
